UNITED STATES PATENT OFFICE.

ROLAND BRIXNER, OF BURBANK, AND WALTER H. CONKLIN, OF LOS ANGELES, CALIFORNIA; SAID BRIXNER ASSIGNOR TO SAID CONKLIN.

DESIGN FOR AN AUTOMOBILE RADIATOR ORNAMENT.

Application filed June 12, 1925. Serial No. 13,766. Term of patent 14 years.

To all whom it may concern:

Be it known that we, ROLAND BRIXNER and WALTER H. CONKLIN, citizens of the United States, residing at Burbank and Los Angeles, respectively, county of Los Angeles, and State of California, have invented a new, original, and ornamental Design for an Automobile Radiator Ornament, of which the following is a specification, reference being had to the accompanying drawing, forming a part thereof.

The figure is a perspective view of an automobile radiator ornament, showing our new design.

We claim:

The ornamental design for an automobile radiator ornament as shown.

R. BRIXNER.
WALTER H. CONKLIN.
